UNITED STATES PATENT OFFICE.

HERBERT J. STRAKER, OF NORTH ATTLEBORO, MASSACHUSETTS, ASSIGNOR TO THE
W. H. SAART COMPANY, A CORPORATION OF MASSACHUSETTS.

DESIGN FOR A BACK FOR BRUSHES, MIRRORS, OR SIMILAR ARTICLES.

No. 39,384.

Specification for Design.

Patented June 30, 1908.

Application filed May 21, 1908. Serial No. 434,196. Term of patent 3½ years.

To all whom it may concern:

Be it known that I, HERBERT J. STRAKER, a citizen of the United States, residing at North Attleboro, in the county of Bristol and State of Massachusetts, have invented a certain new, original, and ornamental Design for a Back for Brushes, Mirrors, or Similar Articles, of which the following is a specification.

The figure is a plan view of a back for a brush, mirror, or similar article embodying my new design.

I claim,

The ornamental design for a back for brushes, mirrors, or similar articles, as shown.

HERBERT J. STRAKER.
